United States Patent Office.

ALBERT MARCELLUS, OF PITTSFORD, NEW YORK.

Letters Patent No. 69,005, dated September 17, 1867.

IMPROVEMENT IN POTATO-DIGGER.

The Schedule referred to in these Letters Patent and making part of the same.

TO ALL WHOM IT MAY CONCERN:

Be it known that I, ALBERT MARCELLUS, of Pittsford, in the county of Monroe, and State of New York, have invented certain new and useful "Improvements in Potato-Diggers;" and I do hereby declare that the following is a full, clear, and exact description thereof, reference being had to the accompanying drawings, making part of this specification, in which—

Figure 1 is a side elevation, having the right-hand mould-board B and shaker G removed, as is also the right-hand side of the frame, and a portion of the driving-gear C.

Figure 2 is a top view of the plough and the shakers.

Figure 3 is a top view of the detachable point p, and a portion of the upright S, to which it is keyed.

Figure 4 is a transverse vertical section in the plane of the red line q, figs. 1 and 2.

Like letters indicate corresponding parts in the several figures. The ground-wheels are only represented by dotted lines W, in fig. 1.

This invention relates to improvements upon my former patent of February 6, 1866, and it consists, mainly, in an improved construction of the plough, in hanging the shakers to the wings of the mould-boards, and in providing suitable means for vibrating or shaking them; also in the manner of raising and lowering the plough.

To enable others to make and use my invention, I will describe its construction and operation.

I carry this machine upon the same style of ground wheels as those patented to me in 1866. I now attach each wheel rigidly to a short shaft, hung in suitable boxes to the under side of the frame. Upon one shaft, A, I hang loosely the spur or driving-gear C, which is driven, when desired, by the sliding-clutch g, which is operated by the hand-lever D, and is held in or out of gear by placing the pin b one side or the other of the lever. The crank-shaft s is driven by the connecting gearing from the ground-wheel shaft A, and it operates or vibrates vertically the shakers G and G'. The ground-wheels may be attached loosely to one long shaft, if desired, and either or both provided with a suitable ratchet. The stock E, supporting the upright S, is made with a long bearing in the rear and on the lower side of the frame, and forward, above it. I provide a friction-roller, r, in the upper side, against which the front edge of the upright S rests. The rear edge is toothed, as shown, and the lever T has a toothed segmental head, H, which engages the upright S. The spring-bolt d also engages the teeth of the upright. This ratchet is withdrawn, when any change is to be made in the gauge of the plough, by means of the hand-lever f, and it is thrown into and retained in gear by the spiral spring R. The lower end of the upright S is shaped as shown in fig. 1, and is cast with a mortise to receive the lug m, cast upon the left wing w', and which reaches through upon the right wing, as shown in fig. 2, and there is a similar projection from the edge of wing w, running under the lug m; or the lugs may be divided, one half being cast upon each wing, one part in front and the other in the rear. The wings are provided with ears y, fig. 1, through which they are bolted to the upright S, and also with a flange, k, at the outer edge, to which the mould-board plates B and B' are bolted. The lug m and projection from wing w are notched, as shown at a, fig. 2, and after being inserted the wings are moved back, as shown, and a wooden key driven through in front at e, which securely locks them to the upright. There may be angle or brace-irons cast to the upper side of the wings w and w', or to the sides of the upright S, for the support of the wings. The plates B and B' are provided with suitable ears, e, to hinge the shakers to, as seen in figs. 1 and 2. The latter receive a vertical vibration or shake by means of the double rod R', fig. 1. The nose-plate P is rounded over the edge of the upright S, and the ends overlap the mould-boards B and B', and are attached to them by screw-bolts. It is firmly held in its position vertically between the notches o and x, fig. 1. The point p is made to fit the notches n and t, which are dovetailed in the edge of the upright. It is provided with a lip, z, on each side, shown in fig. 3, and also represented by dotted lines in fig. 1, which clasp the sides of the upright. It is securely held in position by simply driving in a key, i. The main object in making this point detachable is, that when it becomes useless by being worn and dull, it may be readily detached and a new one substituted. The point where the wear comes is cast upon a chiller. The mould-boards extend nearly to the edge of the ground-wheels.

I am convinced, by a great variety of oft-repeated experiments, that the only really practical way to dig potatoes by machinery is the plan adopted in this machine, viz, to part the hill in the centre, and force it each way into the ground-wheels, from which the potatoes and other coarse substances that will not pass through the

wheels are discharged upon the shakers, where the separation is perfected, and the potatoes deposited in a central row upon the surface of the ground, or upon an elevating-belt, if desired. I have also ascertained, by actual experiment, that when the nose-plate P is rounded in front, and in a vertical position, or nearly so, as shown at *h*, fig. 2, it is impossible to clog the plough with weeds, vines, or similar substances, because they are easily drawn one way or the other across the rounded vertical nose-plate. There may be a sheet-iron guard, a few inches wide, attached to the nose-plate P, and extended back to the front edge of the shakers, to prevent the lodgment or deposit of earth, &c., on the wings. The upright S projects downward below the lower edge of the mould-boards to act as a lateral guide or steady for the machine, which is found to be very essential in the working of this machine.

What I claim as my invention, and desire to secure by Letters Patent, is—

1. The arrangement of the nose-plate P, with its dividing line vertical or nearly so, and rounded, substantially in the manner and for the purposes herein shown and described.
2. The arrangement of the wings *w* and *w'*, in combination with the upright S, to which they are connected suitably, as and for the purposes herein specified.
3. The detachable mould-boards B and B', in combination with the nose-plate P, and the wings *w* and *w'*, when the said mould-boards are arranged with their faces or flat sides vertical, or nearly so, as shown.
4. Hinging the shakers G and G' to the mould-boards, substantially as described, and vibrating them vertically, for the purposes set forth.
5. The arrangement of the toothed upright S, and toothed headed lever T, with the friction-roller *r*, ratchet *d*, and its lever *f*, substantially as shown and described, for the purpose of gauging and adjusting the elevation of the plough.
6. The detachable point *p*, constructed and connected substantially in the manner and for the purposes herein shown and described.

ALBERT MARCELLUS.
